UNITED STATES PATENT OFFICE.

GUSTAVE W. BERTHOLD, OF CHICAGO, ILLINOIS.

CIRCUIT CONTROLLER.

Application filed October 29, 1924. Serial No. 748,584.

My invention belongs to that general class of devices known as circuit controllers, and relates more particularly to a circuit controller arranged to control one or more circuits in predetermined manners to effect predetermined results. The invention has among its objects the production of a device of the kind described that is simple, compact, convenient, reliable, durable, adjustable, efficient and satisfactory for use wherever found applicable. More particularly it has as an object the production of a device of the kind described arranged to control a plurality of circuits to produce predetermined effects. The same is particularly adapted for controlling lights, apparatus and other circuit controllers positioned at more or less remote points. Many other objects and advantages of the construction herein shown and described will be obvious to those skilled in the art from the disclosures herein given.

To this end my invention consists in the novel construction, arrangement and combination of parts herein shown and described, and more particularly pointed out in the claims.

In the drawings, wherein like reference characters indicate like or corresponding parts:

Fig. 1 is a view in elevation of my improved device;

Fig. 2 is a sectional view taken substantially on line 2—2 of Fig. 1;

Fig. 3 is a similar view illustrating a modified type;

Fig. 4 is a similar view illustrating another type;

Fig. 5 is a sectional view taken substantially on line 5—5 of Fig. 1;

Fig. 6 is an enlarged sectional view taken substantially on line 6—6 of Fig. 2;

Fig. 7 is a view similar to Fig. 2, illustrating another modified form;

Fig. 8 is a sectional view taken substantially on line 8—8 of Fig. 7.

Referring to the drawings, in which the preferred embodiments of my invention are shown, and particularly first to Figs. 1, 2, 5 and 6, I provide a plurality of discs 1 suitably spaced and mounted on a shaft 2 carried by standards 3, which may be mounted on the base 10. In the particular embodiment shown, the discs 1 are of conducting material and are spaced from each other by the collars or sleeves 4. Each disc carries one or more adjustable contact members 5,

secured to the disc in any suitable manner. A simple and convenient securing means consists in the bolts carried by the disc and extending through the slot 6 in the member 5. One bolt is preferably headed over as indicated at 8 and the other provided with a thumb nut 7 so that the member may be locked in or out of operative position as desired. For each disc I provide a cooperating contact member 9, which may be of any suitable size, shape and material, that shown being preferably U-shaped so that it will embrace or engage with the contact 5 and form an efficient electrical connection thereat. Contacts 9 are secured to the base 10, preferably insulated from the other parts of the mechanism, by means of bolts 11 or equivalent means for the purpose.

In the particular device shown, it may be mentioned that the circuits may be connected up in any suitable manner. As shown, 15 and 16 represent two mains, 17 illustrating diagrammatically a main controlling switch. One of the mains, as shown in 15, 80 is connected up with the contacts on the discs, as shown, through the supports 3, shaft 2 and discs 1. The contacts 9 are connected with various circuit conductors 18, a separate switch 19 for each contact being provided if desired. I have shown a branch conductor 20 from the member 16, which, with the conductor 18, extends to suitable apparatus, such as lamps 21, other circuit controllers or circuit breakers, motors, and the like, where the same may be applicable.

To control and operate the discs, I have shown a member 22 mounted on the shaft and an operating lever 24 therefor. The disc or member 22 is preferably provided with a plurality of depressions 26 about the periphery thereof. A pin 25 on the lever is a means to cooperate with these depressions and engage therewith so that operating a lever will move 22. This pin 25 is carried by the bracket 27, a spring 28 tending to normally maintain it in operative engaging position. The same is normally maintained against movement by a spring-pressed member 23 carried by the base in the member 29. This spring-pressed stop is provided to prevent accidental turning of the member 22. Grasping the handle and turning the member 22 brings the successive contacts on the discs 1 into engagement with the contacts 9. Obviously, if the next contact on the disc is out of operative position, or, that is, moved

inward as shown at Fig. 2, there will be no circuit closed at that time between the contacts theret.

The device is particularly adapted for use in theaters and the like, for controlling various lighting effects, etc., for the different scenes. For instance, when it is set in one position, as shown in Fig. 1, if it is moved until the next contacts are brought into play, different effects may be instantaneously produced, etc. The discs themselves may contain as many contacts as desired, depending upon the use to which the device is to be put.

15 I have illustrated in Fig. 2 in the dotted lines how the contact 9' may be made of a size that it will bridge over between two of the contacts 5 so that there will be no flickering or changing of the light or control of 20 the apparatus if desired. Obviously, this would only be effective between two adjacent members 5, both in operative relation. If desired, a plurality of contacts 9 and 9' may be maintained at hand and the same interchanged as found desirable. Generally, 25 however, the contact 9 is sufficient.

In the construction shown in Fig. 3, 31 represents the discs provided with the contacts 32, it being understood that there may 30 be any desired number. These contacts are shown adjustably mounted on the discs similar to the construction previously described. In this case, I have shown two contacts 33, each suitably connected in a circuit, only 35 the conductors 34 and 35 being shown. In this case, the circuit is traced through 34, one of the contacts 33, 32, 33 and 35, and the disc shafting, etc., is not used as one of the conductors.

40 In the modified construction shown in Fig. 7, 36 represents a hub mounted on a shaft 37 and provided with a plurality of arms 38 which carry contact members 39 arranged to cooperate with the contact 40. 45 In this case, contact members 39 telescope on the arms 38, but are each normally held in operative engaging position by a spring 41. The sleeve is locked on the arms 38 by a pin 42 or equivalent means. I prefer 50 to provide a bayonet joint connection consisting of the slot 43 and pin 42, so that the member 39 will not become displaced on 38 but may be pushed out of operative position and given a partial turning movement and 55 be locked in an inoperative position as is shown in Fig. 7.

In Fig. 4, I have shown a somewhat modified construction, in which 44 represents a member carrying contacts 45, which may be 60 similar to the type of contact shown in Fig. 8. 46 represents a contacting member arranged to cooperate therewith. One or the

other, that is to say member 44 or member 46 is made movable relative the other so that circuit may be closed between any line 65 of contacts. The effect is substantially similar to any of the constructions shown.

Having thus described my invention, it is obvious that various immaterial modifications may be made in the same without departing from the spirit of my invention; hence I do not wish to be understood as limiting myself to the exact form, construction, arrangement and combination of parts herein shown and described or uses mentioned.

What I claim as new and desire to secure by Letters Patent is:

1. In a device of the class described and in combination, a shaft, a plurality of discs 80 on the shaft in spaced relation, a plurality of adjustable contacts arranged circumferentially of each disc, each contact being formed with a longitudinal slot, spaced bolts carried by the discs and disposed in 85 said slots, and an adjustable thumb nut on one of the bolts in each slot for retaining said contacts in various adjusted positions.

2. In a device of the class described and in combination, a shaft, a plurality of 90 spaced discs on the shaft, contacts carried by each disc, each contact being formed with a slot, bolts carried by said discs and arranged in pairs with one pair disposed in the slot of each contact, one bolt of each 95 pair being headed over forming a stop to limit outward movement of contact, and a thumb nut on the other bolt of each pair to retain said contacts in various adjusted 100 positions.

3. A circuit controller including a support, a shaft having its ends journalled in said support, a plurality of discs mounted upon the shaft and arranged in spaced relation, collars on the shaft between the discs to retain them in spaced relation, a plurality 105 of adjustable contacts carried by each disc, spaced contacts on the support to be engaged by the contacts on the discs, a stop disc on the shaft at one end having spaced depressions in its periphery, a lever loosely mounted on the shaft, a spring pressed pin carried by the lever to engage in any one of 110 said depressions to impart movement to the shaft, and a spring pressed stop member on the support to engage any one of said 115 depressions for retaining the shaft against movement when any of the adjustable contacts on the first discs are engaged with the contacts on the support.

In testimony whereof, I have hereunto signed my name.

GUSTAVE W. BERTHOLD.
